TELEVISION TRANSMISSION METHOD

Kurt Schlesinger, Berlin, Germany, assignor, by
mesne assignments, to Loewe Radio, Inc., a cor-
poration of New York

Application January 7, 1936, Serial No. 57,870
In Germany January 9, 1935

12 Claims. (Cl. 178—7.5)

Heretofore it has been customary to synchronise a television transmission by the fact that at the end of each line and at the end of each picture there have been transmitted a short and long impulse respectively in a certain direction, which impulses exceed the image content signals as regards intensity. The reception of a transmission of this kind was then rendered possible by means of a so-called amplitude filter, 5 i. e., by means of a device which allows the passage of current only above a certain surge value. The surge value of this amplitude filter was then so adjusted in practice that the synchronisation signals, owing to their large amplitude, but not 10 the image signals, were allowed to pass. In this way the synchronisation signals were separated from the image currents.

A disadvantage of this method exists at the transmission end. A certain amplitude range 20 must be reserved solely for the synchronisation signals. The transmitter, therefore, cannot be controlled fully by the image signals alone. In practice two-thirds of the aerial current at the most can be employed for the image signals, and 25 the remaining one-third must be reserved for the synchronisation signals. In the case of weak reception images as such are certainly produced, but the contents of the image are so weakly de- modulated that nothing is to be recognised. A 30 further disadvantage is the fact that strong atmospheric interferences are always able to actuate the synchronising apparatus when their volume of sound exceeds the threshold of response of the filter.

The present invention eliminates these disadvantages by the "time blocking" method. The fundamental idea of this method resides in the following: Between the image-signal receiver and the synchronisation terminals of the scanning apparatus there is provided an amplitude filter 35 of a particular kind, the surge value of which is variable. This filter, as described in the following, is completely blocked for 90% of the line period (blocking phase). During this period it 40 cannot be passed even by the most powerful reception amplitude, and no interferences are able to influence the synchronisation. It is only just before the end of the line is reached that the surge value of the filter is differently adjust- 45 ed. The filter is so biassed that it may now be penetrated by signals of normal reception intensity. A passage of current does nevertheless still not occur (waiting phase). It is only when 50 the transmission during this waiting phase exceeds a certain surge value that the amplitude

filter is passed, and accordingly a synchronisation of the scanning apparatus, takes place (ignition phase). Shortly after the relaxation point of the scanning apparatus has occurred, and accordingly the image point has been thrown back to the other edge of the image, the amplitude filter again returns to the initial condition, i. e., to the blocking phase, and the operation is 5 repeated.

The invention may best be understood by referring to the drawings wherein:

Figures 1a and 1b show image areas for producing picture and synchronizing signals,

Figure 2a shows a curve indicating the relationship between light intensity and antenna current or carrier amplitude,

Figure 2b shows a wave form of the combined picture and synchronizing signals,

Figure 3 shows one form of the present invention, and

Figure 4 shows graphically the voltage variations which occur in the circuit diagram shown in Figure 3.

To the operation as described there belongs a certain form of diagram of the radiated transmission, i. e., a certain nature of the synchronisation signals at the edges of the image. Fig. 25 1a explains these conditions in detail. It is assumed that an image with the image area 1 is given in positive fashion, for example as positive film. The transmitter is modulated with this image content in such fashion that a white point in the image corresponds with a large aerial current, whilst a deep black point in the image causes the aerial current to disappear. The 30 25 characteristic 2 of the transmitter in Fig. 2a represents the connection between the light intensity of the image H and the intensity of the aerial current i. The point $i=0$ is accordingly reached in the case of $H=0$. The transmitter, 40 therefore, is already modulated to the extent of 100% by the image content. The image area 1 in Fig. 1a is made approximately 10% smaller than the sectional area 3 on the Nipkow disc, which is determined by four image points 4. The 45 edge resulting between the sectional area 3 and the image area 1 is light to the extent of one-half by optical means. There is produced an inner margin 5 having a light intensity H_5 . There then remains an outer margin 6, in which 50 any form of lighting completely disappears ($H=0$). The aerial current diagram resulting upon the scanning of a reproduction area of this kind is traced in Fig. 2b against the time. The time sections 7, 8, etc., correspond in each case 55

with a line period. At the end of each line the scanning image point moves over the double edge 5/6. This is a time section 1', 8', which amounts to 10% of the entire period 1/8 of a line (edge period). Within this image margin there arises the "edge signal." The edge signal commences with an intensity H_5 corresponding with the inner margin lighted with this intensity in Fig. 2b. The edge signal terminates with the 10 intensity "0" at that moment when the scanning image point passes into the outer margin 6 in Fig. 1a, because in this phase a lighting of any kind does not occur. The time at which this change-over from H_5 to 0 takes place is designated t_z in Fig. 2b. t_z represents: ignition moment.

Fig. 3 shows an example of a receiver connection for receiving a transmission of the described kind. A heterodyne receiver is supposed; the 20 final tube of the intermediate frequency amplifier is designated 9. This tube is coupled with the twin grid detector tube 11 by means of the transformer 10. The conductivity of this tube decreases and the anode gets more positive when 25 the transmitted intensity increases. The anode is connected to the control grid 16 of the television tube 17 and takes care of the modulation of the electronic ray preceding from the cathode 18 of the television tube. When the aerial 30 current of the transmitter ceases, the anode potential of 11 becomes a minimum and is then merely determined by the anode battery 13, independent of all accidental factors in the reception. The amplitude filter and time blocking 35 devices according to the invention is the tube 14. Its cathode 15 is directly connected to the anode of the detector tube 11, its anode 19 to a counter-potential variable by means of the potentiometer 20. In this lead are inserted the transformers 21 and 22, which separate the synchronization 40 impulses according to their time duration, whereby the transformer 21 having a high natural frequency transmits the short line impulses and the transformer 22 the long frame change 45 impulses to the input of the line (or horizontal) relaxation oscillator 36 and the frame (or vertical) relaxation oscillator 37, respectively, the output of which is connected to the deflecting plates.

50 The operation and use of the transformers 21 and 22 is well known in the art as, for example, in George Patent No. 2,100,279. The relaxation oscillators or beam deflection generators are shown schematically at 36 and 37 since any satisfactory oscillator may be used. An example of such an oscillator is to be found in the U. S. patent to Tolson No. 1,999,378.

55 The feature of the present invention is the function of the twin grids 23, 23' of which 23 is associated with the vertical or frame oscillator while 23' is associated with the horizontal or line oscillator. They attend to the time blocking of the amplitude filter 14 in the following manner:

60 Through the medium of a very large series resistance 24 and a small coupling condenser 26 the control grid 23 is connected to the output of the relaxation oscillator for deflecting the cathode ray towards the synchronization edge of 70 the image. As well known, this plate assumes in the deflecting phase a positive D.-C. potential of continuously increasing amount. This potential is added to the bias 28 imparted to the grid via the leakage resistance 27. The negative bias 28 is selected of such value that merely

the last 10% of the increasing potential of the deflecting plate are able to impart to the grid a weak positive potential.

Fig. 4 shows the temporal course of the line relaxation oscillation such as passes from the 5 left hand image edge 29 to the right hand image edge 30 and assumes the amplitude 30' with positive sign. The bias is designated 31, and is selected to be of such extent that the waiting phase, viz., the time section 32, amounts to approximately 10% of the line period 33. Since the relaxation potential always remains constant, as this is identical with the constant size of the image field in the receiver, and since the bias 28 is also a constant D.-C. potential, the length 15 of the waiting phase 32 may be adjusted to be constant. The curve 34 shows the course adopted by the grid potential of the tube 14 by the action of this coupling with the plate circuit. Owing to the large series resistance 24 of approximately 10^6 20 ohms the grid bias does not continue to increase without limitation, but always remains at the most approximately 1 volt more positive than the particular cathode potential 15. Although, therefore, there is a weak positive grid-cathode 25 bias during the waiting phase no current occurs in the anode circuit 19/20. We are now in the scanning period—which may readily be attained by adjustment of the frequency of the free relaxation oscillation at the receiver—over the inner edge of the edge signal (edge 5, intensity H_5 , Figs. 1 and 2). During this period the detector tube 11 is excited. In consequence the cathode 15 is biased positively in relation to the anode, and although the control grid 23 is in a 35 condition permitting passage no anode current is able to occur. It is only at the ignition point t_z (Fig. 2b), when the scanning point passes over to the outer margin 6, that the aerial current disappears. The cathode then becomes negative 40 in relation to the anode, and since moreover the grid is weakly positive in relation to the cathode a synchronising current impulse now passes through the filter 14. In this way, however, the image point is thrown to the opposite side of the 45 image, i. e., the deflecting plate 25a again becomes negative to the extent of a few hundred volts. The grid 23 of the amplitude filter 14 is again blocked in such fashion that every kind of connection is interrupted between receiving 50 element and synchronising element.

The present specification explains the principle of the invention with the use of a possible connection system of an apparently very particular kind. There are numerous other possibilities of carrying out the idea according to the invention. The advantages of the method will, however, be readily apparent from the above remarks and consist in the following: By adjustment of the surge value of the filter 14 (with 55 the potentiometer 20) fundamentally every synchronisation value may be employed. It is not necessary, for example, to demand that the aerial current is reduced completely to zero in the dark margin 6. During the blocking phase the 60 aerial current may assume any desired value. Operations may even be so performed that the synchronising amplitude is smaller in its absolute value than the maximum amplitudes occurring in the image. This would certainly not 65 result in any advantages in practice, but shows the contradistinction between the time blocking method according to the invention and the method of pure amplitude separation employed at the present time. Interferences are wholly ineffec- 75

tive during the blocking phase. The transmitter may be fully modulated. There may also be transmitted a negative. It is then merely necessary to dispose the inner edge 5 on the opposite side of the image and to locate the reproduction area on the sectional area according to Fig. 1b. The photo-amplifier is increased by a phase-reversing stage. Operations may naturally also be performed with white instead of black outer edges. The synchronising impulses, as explained in Fig. 1, do not require to be produced by optical lighting stages, but may also be produced electrically. Numerous connection systems are known by means of which short impulses can be produced. If an impulse oscillating in one direction is passed to a transformer with tuned natural oscillation and aperiodic damping, there may be derived from the secondary side thereof a single oscillation period of a sine wave which would correspond with a double signal as just described and produced optically and peculiar to the present method.

The duration of the waiting phase must be equal to or greater than the scanning period for the marginal zone of the image. If this condition is not observed and if the waiting phase is too small, the adjustment of the synchronisation is rendered more difficult. Otherwise the adjustment is no more difficult than upon reception of the transmissions heretofore.

As regards the practical execution of an amplitude filter with variable surge value, it may be added that by the introduction of a second grid 23' a coupling may be performed with the vertical plates of the television tube 17. With a tube of this kind having two grids there is solved in the most simple fashion the problem of independent adjustment of image-change signals and line-change signals.

40 I claim:

1. A television receiver for receiving a carrier modulated by picture signals and synchronizing impulses comprising a detector to demodulate the carrier to produce a series of picture and synchronizing signal impulses, a picture reproducing cathode ray tube including a cathode ray beam generating means, a beam modulating electrode and horizontal and vertical electron beam deflecting means, means for impressing the picture signals and synchronizing impulses upon the beam modulating electrode of the cathode ray tube, a synchronizing signal separator tube including a cathode, an output electrode and a pair of control electrodes, means for impressing the produced series of picture and synchronizing signal impulses between the cathode and control electrodes of the separator tube, means for producing electrical energy variations for energizing the horizontal and vertical beam deflecting means, a coupling between the output electrode of said separator tube and said last named means for controlling said means in response to the synchronizing signal impulses, means for biasing the separator tube control electrodes with respect to the cathode to a predetermined blocking potential and means for coupling the pair of control electrodes individually to the horizontal and vertical beam deflecting means so that the normal blocking potential is reduced to a threshold value determined by the deflection so that the separator tube is rendered conductive only during the interval when a synchronizing impulse is received.

2. A television receiver for receiving a carrier modulated by picture signals and synchronizing

impulses comprising a detector to demodulate the carrier to produce a series of picture signals and synchronizing impulses, a picture reproducing cathode ray tube including a cathode ray beam generating means, a beam modulating electrode 5 and electron beam deflecting means, means for impressing the produced series of picture signals and synchronizing impulses upon the beam modulating electrode of the cathode ray tube, a synchronizing signal separator tube including a cathode, an output electrode and a control electrode, means for impressing the synchronizing signal impulses on the cathode of the separator tube, means coupled to the output electrode of said tube for producing beam deflection voltage variations for controlling the electron beam deflecting means in a predetermined operational cycle in response to the synchronizing impulses, means for biasing the control electrode of the separator tube to a predetermined normal potential with respect to the cathode of the separator tube to render the tube normally inoperative, and a capacitive connection between the control electrode of the separator tube and the beam deflecting means to condition the separator tube in such a manner that the bias voltage is substantially neutralized at a predetermined time in the deflection cycle so that the separator tube is rendered conductive only during the interval when a synchronizing impulse is received.

3. A television receiver for receiving a carrier modulated by picture signals and synchronizing impulses comprising a detector to demodulate the carrier to produce a series of picture signals and synchronizing impulses, a picture reproducing cathode ray tube including a cathode ray beam generating means, a beam modulating electrode and horizontal and vertical beam deflecting means, means for impressing the produced series of picture signals and synchronizing impulses upon the beam modulating electrode of the cathode ray tube, a tube including a cathode, an output electrode and a pair of control electrodes for separating the synchronizing signals from the picture signals, means for impressing the picture signals and the synchronizing impulses on the cathode of the separator tube, means coupled to the output electrode of said tube for producing beam deflection voltage variations for energizing the horizontal and vertical beam deflecting means in response to the synchronizing impulses, means for biasing the control electrodes at a predetermined potential with respect to the cathode of the separator tube and means for coupling the pair of control electrodes to the horizontal and vertical beam deflecting means respectively, whereby the separator tube is conditioned for conduction only in accordance with the time of receipt of synchronizing signalling impulses.

4. A television receiver wherein a series of picture signals and synchronizing impulses are used to produce a television picture comprising a cathode ray tube, means for generating a beam of electrons in the tube, means for modulating the beam of electrons and means for deflecting the beam of electrons in substantially mutually perpendicular directions, deflection voltage generating means for energizing the beam deflecting means, a discharge tube including a cathode, a control electrode and an anode, means for impressing the picture signals and synchronizing impulses upon the cathode of said tube, synchronizing impulse responsive means connected to the anode of said tube for controlling the deflection voltage generating means, means for biasing the

control electrode to a predetermined potential relative to the cathode, and capacitive coupling between the control electrode and the deflection voltage generating means to control the conductive periods of the discharge tube.

5. A television receiver wherein a series of picture and synchronizing signal impulses are used to produce and synthesize a television picture comprising a cathode ray tube, means for generating a beam of electrons in the tube, means for modulating the beam of electrons under the control of the said signals and means for deflecting the beam of electrons in mutually perpendicular directions, means for generating electrical energy for energizing the beam deflecting means, a discharge tube including a cathode, a control electrode and an anode, means for impressing at least the synchronizing signal impulses upon the cathode of said tube, means connected to the anode of said tube and responsive to the synchronizing signal impulses for controlling the deflection energy generating means, means for biasing the control electrode to a predetermined potential relative to the cathode to maintain said tube normally inoperative and means for coupling the control electrode to the deflection energy generating means to supply to said tube an auxiliary bias of opposite polarity which reaches a maximum immediately prior to the time of the arrival of each synchronizing impulse and is of a lesser magnitude than the first named bias so that the said tube is rendered conductive immediately upon and only during intervals when synchronizing impulses are received.

35. 6. A television receiver wherein a series of picture signals and synchronizing impulses are used to produce a television picture comprising a cathode ray tube, means for generating a beam of electrons in the tube, means for modulating the beam of electrons and means for deflecting the beam of electrons in substantially mutually perpendicular directions, deflection energy generating means for energizing the beam deflecting means, a discharge tube including a cathode, a control electrode and an anode, means for impressing the synchronizing impulses between the cathode and control electrode of said tube, synchronizing signal impulse responsive means connected to the anode of said tube for controlling the deflection energy generating means, means for biasing the control electrode to a predetermined negative potential relative to the cathode to normally prevent conduction in the tube, and means including an electron storage means for coupling the control electrode to the deflection energy generating means whereby the bias on said tube is reduced at a time immediately prior to the receipt of a synchronizing impulse to a value such as to render the tube responsive to the synchronizing impulses only during a time interval approximating the time of arrival of each synchronizing impulse.

7. A television system wherein a series of picture signals and synchronizing impulses are used to produce a television image including a picture producing cathode ray tube, means in said tube for generating a focused beam of electrons, means for deflecting the beam of electrons, deflection energy generating means for energizing the beam deflecting means, a discharge tube including a cathode, a control electrode and an anode, means connected to said anode responsive to synchronizing impulses for controlling the deflection energy generating means, means for applying the series of picture signals and synchronizing im-

pulses between the cathode and the control electrode of said tube, means for biasing the control electrode at a predetermined potential relative to the cathode to normally prevent the flow of electronic current through the tube, and means for coupling the control electrode to the deflection energy generating means whereby the bias on said tube is so reduced as to render the tube responsive to the synchronizing impulses only during a time interval approximating the time of arrival of each synchronizing impulse.

8. A television system wherein a series of picture signals and synchronizing impulses are used to produce a television image including a picture producing cathode ray tube, means for generating a beam of electrons in said tube, means for modulating the intensity of the beam of electrons, means for deflecting the beam of electrons in substantially mutually perpendicular directions, relaxation oscillator deflection voltage generating means for energizing the beam deflecting means, a discharge tube including a cathode, a control electrode and an anode, means connected to said anode responsive to synchronizing impulses for controlling the deflection voltage generating means, means for applying the series of picture signals and synchronizing impulses to the cathode of said tube, means for biasing the control electrode to a predetermined negative potential relative to the cathode normally to prevent the flow of electronic current through the tube and means for coupling the control electrode to the deflection voltage generating means whereby the discharge tube is conditioned for conduction immediately prior to the application of a synchronizing impulse.

9. In a television system wherein a series of picture signals and synchronizing impulses are received and used to control and synthesize respectively the production of an electro-optical image, an image producing cathode ray tube having a target element, means in said tube for generating a beam of electrons and for directing the beam upon the target, means for modulating the intensity of the beam of electrons to control the intensity of the electro-optical images developed on the target, means for deflecting the beam of electrons in substantially mutually perpendicular directions, deflection energy generating means for energizing the beam deflecting means, a discharge tube including a cathode, a control electrode and an output electrode for separating the synchronizing and picture signals, means connected to said output electrode and responsive to the separated synchronizing impulses for controlling the deflection energy generating means, means for applying the series of picture signals and synchronizing impulses between the cathode and control electrode of said tube, means for biasing the control electrode to a predetermined negative potential relative to the cathode normally to prevent the flow of electronic current through the tube and a storage means for coupling the control electrode to the beam deflection energy generating means to reduce the magnitude of the applied bias to a predetermined minimum value which is attained at a time period immediately prior to the normal period of receipt of synchronizing signal impulses whereby the discharge tube is rendered conductive only upon the application of synchronizing signal impulses thereon which serve to synthesize the electro-optical image.

10. A television receiver including means for amplifying a radio frequency carrier amplitude

- modulated by a series of picture signals and synchronizing signal impulses, detector means for converting the said signals into demodulated picture signals and synchronizing signal impulses, 5 a picture reproducing cathode ray tube including means for producing a beam of electrons, means for modulating the beam of electrons, means for deflecting the beam in a predetermined direction and means for deflecting the beam in a substantially mutually perpendicular direction, beam deflection generators connected respectively to the said beam deflecting means for developing energy to deflect said beam in predetermined deflection cycles, a discharge tube including a cathode, a pair of control electrodes and an output electrode, means for impressing the picture signals and the synchronizing impulses between the cathode and control electrode of said discharge tube and also upon the electron beam modulating electrode, synchronizing impulse differentiating means connected to the output electrode of said tube for controlling the operation of the beam deflection generators to maintain the predetermined cycles under the control of received 20 signals, means for biasing said control electrode relative to the cathode to a predetermined negative potential sufficient normally to prevent conduction within the tube, and capacitive means for separately coupling the control electrodes to each of the beam deflection energy generators so as ultimately to reduce the bias to predetermined threshold value at a time immediately preceding the arrival of synchronizing impulses whereby the tube becomes substantially instantaneous conducting at time periods when synchronizing impulses are impressed thereon.
11. A television receiver including means for amplifying a radio frequency carrier amplitude modulated by a series of picture signals and synchronizing impulses, detector means for producing demodulated picture signals and synchronizing impulses, a picture reproducing cathode ray tube including means for producing a beam of electrons, means for modulating the beam of electrons, means for deflecting the beam in a vertical direction and means for deflecting the beam in a horizontal direction, vertical and horizontal beam deflection generators connected respective-

ly to the vertical and horizontal beam deflecting means, a discharge tube including a cathode, a pair of control electrodes and an anode, means for impressing the picture signals and the synchronizing impulses upon the cathode of said tube and upon the electron beam modulating electrode, synchronizing signal impulse differentiating means connected to the anode of said tube for controlling the operation of the beam deflection generators, means for biasing said control electrodes to a predetermined negative potential relative to the cathode to normally prevent conduction of the tube, and means including condensers for coupling the control electrodes respectively to the beam deflection generators whereby the bias on said tube is reduced during each deflection cycle in order that the tube will become conductive only when synchronizing impulses are impressed thereon.

12. A television receiver including means for amplifying a radio frequency carrier amplitude modulated by a series of picture signals and synchronizing impulses, detector means for producing demodulated picture signals and synchronizing impulses, a picture reproducing cathode ray tube including means for producing a beam of electrons, means for deflecting the beam in a vertical direction and means for deflecting the beam in a horizontal direction, vertical and horizontal beam deflection generators connected respectively to the vertical and horizontal beam deflecting means, a discharge tube including a cathode, a pair of control electrodes and an anode, means for impressing the synchronizing impulses between the cathode and control electrode of said tube, synchronizing impulse responsive means connected to the anode of said tube for controlling the operation of the beam deflection generators, means for biasing said control electrodes to a predetermined potential relative to the cathode normally to prevent conduction within the tube, and means for coupling the control electrodes to the beam deflection generators whereby the control electrodes will be made less negative with respect to the cathode at intervals immediately preceding the arrival of synchronizing impulses.

KURT SCHLESINGER.
